SMOKE JACK FOR DIESEL LOCOMOTIVES

Harold Knutson and Harold G. Knutson,
Chicago, Ill.

Application November 12, 1949, Serial No. 126,854

3 Claims. (Cl. 104—52)

1

This invention relates in general to a movable smokejack, particularly intended for diesel locomotive round houses, although it may have a more general use wherever applicable.

In servicing diesel locomotives in an engine house, the fumes are dangerous, damaging and disagreeable, and because of the short stacks or discharge pipes, the ventilating means must be closely adjustable over the top of the discharge pipe which usually projects only a short distance above the top of the diesel engine.

The present invention provides an adjustable jack or stack which may be easily moved closely over the diesel engine discharge pipe and free from such engagement.

An important object of the invention is to provide a vertically movable mounting for a discharge stack which may also be applied to an inclined roof or support.

A further object of the invention is to automatically close the smoke stack when the smoke jack is raised from its smoke receiving position.

Still a further object of the invention is to limit the movement of the smoke jack from descending too far.

Other objects of the invention will appear in the specification and will be apparent from the accompanying drawings in which,

Fig. 1 is a side elevation with some of the parts shown in section of a ventilator construction in accordance with this invention and in lowered position;

Fig. 2 is a similar view showing the parts in raised position; and

Fig. 3 is a sectional view taken on the line 3—3 of Fig. 2;

For diesel engines, it is necessary to have a closer adjustment and movement of the smoke jacks in order to receive the smoke and vapors therefrom and to discharge it from the engine house. It is also desirable to insure a proper draft for the smoking fumes regardless of the direction of the wind and to close the stack entirely when it is not in use.

The present invention provides an adjustable hood which may be moved to any extent and when raised, it closes the smoke stack.

Referring now more particularly to the drawings, the smoke jack comprises a circular vertical stack 10 connected at its lower end to the circularly reduced upper end of a hood 12 which is preferably rectangular at its bottom. In the hood, and extending upwardly together at opposite sides of the center, are deflector plates 14 which extend about half of the height of the

10

hood and transversely thereof to the opposite sides, and being spaced apart at the top to allow a free passage of gases therethrough. Should the stack of any locomotive be located between the two plates 14 or at either side thereof relative to the front or rear of the hood, the exhaust therefrom will be directed upwardly into the circular stack 10 and will not tend to swirl around in the hood 12.

Above the stack 10 and fitting closely but slidably therearound is a fixed circular stack 16 having a supporting ring 18 at its lower end engaged by angle bar cross pieces 20 for rigidly supporting this stack in connection with roof rafters 22 and other superstructure 24 of an engine house. Usually the roof is inclined in one direction or the other, represented by the position of the rafters at opposite sides of the stack to provide an outlet chamber 26 therefor, and any suitable supports such as guy-rods 28 and 30 of various lengths may be provided for securing the cross bars 20 to the rafters and thus holding the stack 16 in a fixed vertical position. At the upper end of the stack is a canopy 32 having a round end 34 for engaging the upper end of the stack and a flanged rectangular base 36 for engaging the upper end of the superstructure 34.

Attached at opposite sides of the hood 12 are angle bar side braces 40 to the ends of which are connected wire cables 42 which extend over pulleys 44 mounted in a ring 46 secured to the upper fixed stack 16. The outer ends of the wire cables extend around fixed pulleys 48 carried by a cross piece 20 or any other fixed support and directing the cables together so that they can be simultaneously operated.

Within the fixed stack 16 is a damper 50 pivoted at opposite sides and one end engaged by an arm 52 outside of the stack. The other end of the arm is pivotally engaged by an upper end of a rod 54, the lower end of which extends into the path of one of the side braces 40 and is of such a length that when the hood 12 is raised a predetermined amount, the lower end of the bar will be engaged, thus moving the arm 52 and closing the damper in the stack 16.

To limit the downward movement of the hood 12, a chain 56 at each side of the hood is attached at its upper end to the cross piece 20 and at its lower end to a clip 58 secured to the side of the hood 12. When the hood is raised, the chains are loosely looped at the sides and when the hood is lowered, the chains limit the downward movement thereof.

At the top of the fixed stack 16 is a ventilator which fits tightly over the end of the stack with a surrounding shell 70 spaced outwardly by a circular inclined deflector ring 74, the lower end of which is below the upper edge above the lower edge of the shell 70, this ring partially closing the space between the stack and the shell 70.

At the top of the ventilator is a conical cap 80 with its apex above the shell 70 and the lower edge or base of the cap extending below the top of the sleeve. Between the inside of the shell 70, and the outer edge of the cap 80 and the outer edge of the ring 74, there is an outer space providing a plurality of paths for smoke and fumes from the ventilator. The outer shell 70 preferably is non-circular provided with alternate large and small flat portions 84 and 86 respectively. The specific construction of the ventilator forms no particular part of the present invention.

With a smoke jack of this construction, the lowering of the smoke collecting hood opens the damper in the fixed portion of the stack and the smoke and gases pass upwardly through the movable and fixed portions of the stack and through the ventilator. The passage of the smokes and gases is unobstructed at all times because the ventilator is always open and if a wind is blowing in any direction, the air currents engaging the ventilator will cause an additional impelled flow of the gases out of the stack.

While we have thus described this construction in some detail, it should be regarded by way of example and illustration rather than as a limitation or restriction of the invention as various changes in the construction, combination and arrangement of the parts may be made without departing from the spirit and scope of the invention.

We claim:

1. In a smoke jack, a movable stack section having a downwardly flaring hood at the bottom thereof, a fixed stack section in which the upper end of the movable stack is slidable, a damper in the fixed stack section, a crank arm for the damper extending to the outside of the fixed stack; a rod connected at its upper end to the

outer end of the crank arm, the lower end of the rod extending downwardly in the path of the movable hood but spaced from the hood in its lowered position so that the hood must be raised a predetermined amount before the end of the arm is engaged, and means to raise and lower the hood thereby engaging the rod to close the damper when the movable hood is raised a predetermined amount.

2. In a smoke jack in accordance with claim 1, a horizontal cross piece connected to the hood, means to raise and lower the hood comprising cables connected to the end of the cross piece and pulleys connected to the fixed stack section to raise and lower the movable stack section, and the cross piece being in the path of the lower end of the rod but spaced therefrom when the hood is at the lower end of its path so that the hood must be raised a predetermined amount before the rod is engaged by the cross piece to close the damper.

3. In a smoke jack in accordance with claim 2, the hood at the bottom of the movable stack section being substantially rectangular at its outer flaring ends, and partition plates extending across within the hood from the lower opening thereof and inclined toward each other and toward the sides of the hood but terminating at a distance from the junction of the hood with the stand to divide the hood into a number of chambers all merging together in a common chamber at the reduced portion of the hood for entrance together into the stack.

HAROLD KNUTSON.
